[57] CLAIM

The ornamental design for a price tag holder or similar article, as shown and described.

DESCRIPTION

FIG. 1 is a top plan view of a price tag holder or similar article showing my new design;

FIG. 2 is a front elevational view thereof;

FIG. 3 is a rear elevational view thereof;

FIG. 4 is a bottom plan view thereof;

FIG. 5 is a side elevational view thereof, with the opposite side being a mirror image;

FIG. 6 is a sectional view taken along line 6—6 of FIG.

1 thereof; and

FIG. 7 is a perspective view thereof.

FIG. 6
